DROP BOTTOM MINE CAR

Thomas Earl Bowen, Birmingham, Ala., assignor
to Empire Industries, Inc., New York, N. Y., a
corporation of Delaware

Application March 12, 1949, Serial No. 81,145

7 Claims. (Cl. 105—253)

1

This invention relates to mine cars and more particularly to the type known as drop bottom cars.

It is an object of the invention to provide a drop bottom mine car which is automatic in operation wherein the bottom doors are hinged at their forward ends, the fore door being mounted on a hinge rod rotatable in the side sills and the aft door being mounted on a hinge rod having journals rotatable in bearings which are in turn rotatable and movable longitudinally relative to the side sills whereby friction between the operating parts is reduced to a minimum. When the doors are in closed position the rear end of the aft door is held closed by a latch, the forward end of the aft door then providing an abutment upon which the rear end of the fore door rests to keep it closed. When the latch is released, the aft door swings downwardly on its hinge rod and meantime during this opening movement of the aft door, the aft door moves backward bodily on the frame to remove the abutment upon which the rear end of the fore door was resting thereby causing the fore door to swing downwardly to open it.

Although the novel features which are believed to be characteristic of the invention will be pointed out in the annexed claims, the invention itself as to its objects and advantages and the manner in which it may be carried out may be better understood by reference to the following description taken in connection with the accompanying drawings forming a part hereof, in which

Fig. 1 is a top plan view of the bin or bed of the car partly broken away;

Fig. 2 is a view in elevation on line 2—2 of Fig. 1;

Fig. 3 is a view in elevation looking toward the rear end of the car on line 3—3 of Fig. 2 and partly broken away to show the latching arrangement for the aft door;

Fig. 4 is an end view of the car in elevation looking toward the rear end;

Fig. 5 is a plan view on line 5—5 of Fig. 2 with part of the fore door broken away;

Fig. 6 is a side view in elevation of the car partly broken away and showing the fore door in up position and the aft door prior to final closing;

Fig. 7 is a view to smaller scale showing the mine car at a tipple with both doors open;

Fig. 8 is a view in elevation showing a modified form of the rear door hinge mounting; and

Fig. 9 is a view at right angles to Fig. 8.

Referring now to the drawings, in which like

2

reference characters denote like parts throughout the several views, the car comprises a main frame consisting of side sills 10 and 11 and end sills 12 and 13 fastened together in the usual way as by welding, or riveting as known in the art. The sills are of standard structural steel channel members of suitable size and strength. The frame is mounted on wheels 14, 15, 16, 17 carried on the axles 18, 19 extending through apertures in the webs of the side sill channel members 10, 11 and supported in axle boxes 20, 21, 22, 23 which may be of known design.

The frame carries a bed consisting of side walls 24 and 25, end walls 26 and 27, and the doors 28 and 29 which provide a bottom for the bed of the car. As shown, side walls 24 and 25 have a vertical portion 30 and 31 and an inclined portion 32 and 33 terminating in a vertical portion 34 and 35 flush with the vertical web portions of the side sills 10 and 11. The end walls 26 and 27, as shown, have vertical portions 36 and 37 and inclined portions 38 and 39 which extend over the axles 18 and 19. The bed is suitably reinforced by angle irons 41 transverse of the car bed and otherwise as may be desired. It will be manifest that the car frame lends itself to other types of bed side walls and end walls, the selection being frequently governed by the particular conditions existing at a particular mine, as to height, tracks, clearances, and other factors to be reckoned with.

The fore door 28 of the bottom is mounted between the side sills 10 and 11. This door at its forward end is secured to a hinge rod 40. The hinge rod 40 is mounted to rotate on its axis in holes 41 and 42 in the vertical webs of the side sills (see Fig. 5), it being noted that the holes extend through reinforcing plates 43 and 44 welded to the side sills. Cotter pins 45 and 46 in the hinge rod maintain it in place for rotation in the holes 41 and 42 which provide bearings in which the rod is rotatable. When not held up in closed position as shown in Fig. 2, the fore door 28 is free to swing downwardly on the pivot provided by the hinge rod 40 as indicated in dot-dash lines 28a. It will be observed that the fore door 28 has a downwardly inclined portion 50 at its front end, a flat bottom portion 51 in the middle, and at its rear end an upwardly inclined portion 52. It is reinforced by vertical side plates 53 and 54 and a vertical center plate 55.

The aft door 29 is of substantially the same shape as the fore door, having its forward end secured to a hinge rod 56 mounted transverse of the car. It has similar reinforcing side plates

57 and 58 and center plate 59, as does the fore door. It likewise has an inclined portion 60 at its forward end, a flat portion 61 in the middle, an inclined portion 62 and a flat rear portion 63. However, the aft door hinge rod 56 is mounted differently from the fore door hinge rod 40 as described more in detail hereinafter. The flat rear end portion 63 of the aft door 29 has a rearwardly extending pin 64 secured at the center of the door to cooperate with a latch mechanism designated generally by reference numeral 65. The rear end of the aft door 29 is cut away at the corners as shown at 66, 67. It has a pin 68 secured to the bottom of the door portion 63 and parallel with the end of the door, this pin providing a stub shaft upon which is mounted a cam roller 69 for rotation on this shaft. This roller, as will be described hereinafter, engages and rolls on an upwardly and forwardly inclined wedge 70 which is secured to the frame. The wedge provides a cam face 71 so that when the roller rolls up the cam face 71 it forces the aft door 29 forward relatively to the frame of the car. Although only one such roller and wedge is shown, a like arrangement can be provided at the cut out portion 67 at the opposite corner so as to provide two rolls and wedges if desired.

The latch mechanism 65 comprises a latch member 72 mounted for pivotal movement about a pivot pin 73. The pivot pin 73 is mounted in a bracket 74 secured to the web of end sill channel iron 13 and hence is held in fixed position on the frame of the car. The pivoted latch member 72 has a cut out portion providing an inclined cam face 75 which engages a pin 76 fixed to a lever bar 77. The lever bar 77 is pivoted at its end on a pivot pin 78 secured to a vertical angle iron 79 which is welded to the frame and bed. The lever bar 77 extends through a slot in the web 80 of angle iron 79 and through a slot in the web 81 of a similar angle iron 82 on the other side of the rear end of the car. The lever arm 77 has a short downwardly bent portion 83 extending beyond the left rear wheel 16 of the car, to engage a trip cam 84 (see Fig. 7) which may be placed at a desirable place along the track 85 in which the car or a train of cars operates. The lever bar pin 76 is vertically slidable in a guide slot 86 provided in a vertical plate 87 secured at its upper end to the bed of the car and at its lower end to the end sill 13.

The pivoted latch member 72 below its pivot 73 has a notch 88 providing a shoulder 89 upon which the door pin 64 can rest to maintain the aft door 29 in its up or closed position. Beneath the shoulder 89 is an inclined cam face 90. It may engage the door pin 64 when the aft door 29 is raised from its down or open position to its up or closed position. A yieldable helical spring 91 secured to the upper end of the latch member 72 and to the bed normally urges the latch member in a counterclockwise direction about pivot 73 as viewed in Fig. 3.

The center hinge rod 56 is mounted for rotation about its axis and also for movement bodily backward and forward relative to the side sills of the car, the hinge rod being mounted on rollers which may roll on trackways on the side sills. It will be observed that the forward end portion of the door 29 is bent around the hinge rod 56 forming a loop 94. The loop may be formed so that the hinge rod rotates in it or it may be formed so that the hinge rod is fixed to it so that it does not rotate in the loop. Likewise the forward end portion of door 28 has a loop 95 which

may be mounted in similar fashion on hinge rod 40.

The ends of hinge rod 56 extend through elongate guide slots 96 and 97 (see Fig. 5) in the webs of side sills 10 and 11. The slots are similar and are inclined downward toward the rear as shown in Fig. 2. Reinforcing plates 98 and 99 (see Fig. 5) having slots registering with the slots in the side sills are provided to strengthen the side sills because of the cutting away of the webs to form the slots. Mounted for rotation on each end of the hinge rod 56 is a hinge rod roller 100 and 101. These rollers may roll on plates forming guide tracks 102 and 103 which are secured to the reinforcing plates 98 and 99. The trackways are mounted parallel with the slots 96 and 97. The hinge rod is rotatable in the rollers; thus the rollers 100 and 101 provide bearings which themselves are movable longitudinally of the frame when the hinge rod 56 is moved bodily in the slots, since the rollers 100 and 101 roll on the trackways 102 and 103.

It will be observed that when the fore door 28 is in up or closed position and the aft door 29 is in up or closed position as shown in Fig. 2, the aft door is forward in the guide slots 96 and 97 and the loop 94 of the aft door provides a stop or rest on which the rear end of the fore door 28 rests to maintain the fore door in closed position. The aft door 29 is maintained in forward position by the wedge 70 and in up or closed position by pin 64 which rests on shoulder 89 of the latch member 72.

When the latch member 72 is actuated by lifting the lever rod 77, the latch member is rotated in clockwise direction as viewed in Fig. 3 and this removes the shoulder 89 from under the pin 64 permitting the rear end of door 29 to fall. This movement of latch member 72 is brought about because pin 76 of the lever bar engages cam face 75 and when the pin 76 of the lever is raised in the slot 86 the latch member 72 is rotated on pivot pin 73 to move shoulder 89 out from under the pin 64.

The car operates as follows. It may be assumed the doors 28 and 29 are in closed position as shown in Fig. 2 and loaded with coal. The car moves on tracks 85 in the direction of the arrow (see Fig. 7). When the rear end of the car passes the trip cam 84 which may be placed along the track, the outer end 83 of lever bar 77 engages the cam 84 and is raised to rotate lever arm 77 on its pivot 78. This causes the latch member 72 to rotate on its pivot 73 to withdraw the shoulder 89 from beneath pin 64 of the aft door 29. The weight of the coal will cause door 29 to swing down, about the axis of hinge rod 56. In the meantime the downward movement of the rear end of door 29 permits the door to move bodily toward the rear, the roller 69 rolling on cam face 71 of wedge 70. The hinge rod 56 moves rearwardly relative to the side sills in slots 96 and 97, the hinge rod rollers 100 and 101 rolling rearwardly on the trackways 102 and 103. Upon this rearward movement of the hinge rod 56, the loop 94 upon which the rear end of door 28 was resting is removed from beneath the door 28, whereupon this fore door swings downwardly about the axis of its hinge rod 40. The trip cam 84 will, of course, be set to release the doors to dump the coal at the tipple 105 and the doors 28 and 29 will hang as shown in Fig. 7.

As the car moves forward, the fore door engages a cam section 106 located between the tracks. A friction plate 107 on the fore door is

such that as the car moves forward the door 28 is swung upwardly on hinge rod 40 so that its rear end is sufficiently high to permit the loop 94 to move in under it. When the aft door reaches the cam section 106 its friction plate 108 engages the cam and the rear door is raised. When it is swung up sufficiently high for the roller 68 to engage the wedge 70 the aft door 29 is forced forwardly and when the roller reaches the upper end of the cam face 71 the hinge rod 56 has moved forward in the slots 96 and 97 so that the loop 94 is beneath the rear end of the fore door. In its upward swing movement the pin 64 engages the cam face 90 of the latch member 72 causing it to rotate on its pivot against the force of yielding spring 91 and finally the spring 91 causes the latch member to return when the pin 64 is opposite the notch 88 and the shoulder 89 moves in under pin 64 to maintain it and the door 29 in up or closed position. Meantime the car passes track cam section 106 and the bottom doors remain closed until they are again tripped by raising lever bar 71.

A modified form for mounting the aft door hinge rod is shown in Figs. 8 and 9. In this modified form the aft door 29a which is like door 29 of the form shown in Figs. 1-7, is mounted on hinge rod 56a in the same way as described hereinbefore. This center hinge rod 56a for the aft door extends through arcuate slots 97a, it being understood that each side sill has a similar arrangement. It is deemed therefore to be sufficient to describe only one, as shown in Figs. 8 and 9. The side sill 11a is reinforced with a plate 99a which has an arcuate slot registering with the slot in the web of the side sill. Beneath the slot and substantially parallel thereto and secured to plate 99a is trackway plate having an arcuate trackway 103a upon which the hinge rod roller 101a rolls. The roller 101a is like roller 100 shown in Figs. 1-7. The hinge rod at its end outside the roller 101a is mounted on a hinge rod link 110a which has a bore at its lower end in which the hinge rod 56a is rotatably mounted. The hinge rod is held in place as by a cotter pin 112a. The upper end of this link 110a is pivotally mounted on a stud bolt 111a which is secured to the reinforcing plate 99a; a spacer 112a being provided to keep the link lined up with the outside of roller 101a. The link 110a and trackway 103a is so arranged that when the hinge rod 56a is moved backward in the door-opening operation, the hinge rod swings on the pivoted link 110a and the roller 101a rolls backwardly on the downwardly inclined arcuate trackway 103a. And when the aft door is closed the reverse movement takes place, that is, the hinge rod 56a then moves forward by swinging on the pivoted link 110a to the forward end of the slot 97a while the roller moves forward along trackway 103a. Thus the weight of the door is nicely distributed. It will be understood as mentioned above that both ends of hinge rod 56a are arranged in the same way and operate in similar fashion. Also, it may be noted that this arrangement is such that the forward end of aft door 29a forms an abutment for the fore door in similar manner as the form shown in Figs. 1-7 and is removed from under the rear end of the fore door in similar fashion.

The terms and expressions which have been employed herein are used as terms of description and not of limitation and there is no intention in the use of such terms and expressions of excluding any equivalent of the features shown

and described or portions thereof, but it is recognized that various modifications are possible within the scope of invention claimed.

What is claimed is:

- 5 1. A drop bottom mine car which comprises side sill members and end sill members providing a frame, axles and wheels carrying said frame, a plurality of drop bottom doors including a fore and an aft door pivotally mounted in tandem between said side sills and forming a bottom for said car, a rotatable fore door hinge rod mounted transverse of the side sill members, the forward end of the fore door being secured thereto, a rotatable aft door hinge rod 15 transverse of the side sill members, the forward end of the aft door being secured thereto, a roller mounted on each end of said aft door hinge rod, a trackway on each side sill providing means for rolling movement of said rollers back and forth 20 a limited distance relative to said side sills, latch mechanism on said frame for maintaining said aft door in closed position and for releasing said aft door whereby it will open by downward swinging movement about the axis of its hinge rod, 25 wedge means on said frame for engaging the aft door at its rear end to force said door to move forward bodily on said rollers so that its forward end provides a rest for the rear end of the adjacent fore door to maintain said fore door in closed position, said aft door moving rearwardly and bodily when said aft door swings downwardly upon release of said latch mechanism thereby withdrawing said rest from beneath said fore door thereby causing said fore door to open by swinging downwardly about the axis of its hinge rod and said aft door moving forwardly and bodily when said aft door swings upwardly to closed position whereby the forward end of the rear door forms a rest for the rear end of the fore door when said fore door is in closed position.
2. A drop bottom mine car which comprises a pair of side sill members and end sill members providing a frame, side and end walls carried on the frame, a fore door and an aft door in 45 tandem between said side sills, a rotatable fore door hinge rod mounted transverse of said side sills and having the forward end of said fore door secured thereto, said hinge rod providing a pivot mounting about which said fore door may swing downward for opening, a rotatable aft door hinge rod mounted transverse of said side sills and having the forward end of said aft door secured thereto, a roller mounted on each end of said aft door hinge rod, a trackway on 50 each side sill providing means for rolling movement of said rollers thereon a limited distance back and forth along said frame, said aft door hinge rod, rollers, and trackways providing pivot mounting means whereby said aft door may swing downwardly about its hinge rod axis during opening movement and whereby said aft door hinge rod moves backward on the frame during the opening movement and forward on the frame during the closing movement of said aft door, the forward end of said aft door providing a rest upon which the rear end of said fore door rests when the fore door is in closed position and said aft door hinge rod is in forward position, wedge means on said frame to engage said aft door and force it and its hinge rod to forward position during the closing movement of said aft door so that its forward end is under the rear end of the fore door when the fore door is swung up to closed position, latch mechanism operative 55 to hold said aft door in closed position and to

release said aft door for opening, said aft door on its opening movement swinging downwardly about the axis of its hinge rod and its said hinge rod moving backwardly along said frame thereby removing said rest from beneath said fore door for opening said fore door.

3. A drop bottom mine car which comprises a pair of side sill members and end sill members providing a frame, a fore door and an aft door in tandem between said side sills, a rotatable fore door hinge rod mounted transverse of said side sills and having the forward end of said fore door secured thereto, said hinge rod providing a pivot mounting about which said fore door may swing downward for opening, a rotatable aft door hinge rod mounted transverse of said side sills with its ends extending through elongate slots in said side sill members and having the forward end of said aft door secured thereto, a roller mounted on each end of said aft door hinge rod, a trackway on each side sill adjacent its elongate slot providing means for rolling movement of said rollers thereon a limited distance back and forth along said frame, said aft door hinge rod, rollers, and trackways providing means whereby said aft door may swing downwardly about its hinge rod axis during opening movement and whereby said aft door hinge rod moves backward on the frame within said slots during the opening movement and forward on the frame within said slots during the closing movement of said aft door, the forward end of said aft door providing a rest upon which the rear end of said fore door rests when the fore door is in closed position and said aft door hinge rod is in forward position in said slots, wedge means on said frame to engage said aft door and force it and its hinge rod to forward position in said slots during the closing movement of said aft door so that its forward end is under the rear end of the fore door when the fore door is swung up to closed position, latch mechanism operative to hold said aft door in closed position and to release said aft door for opening, said aft door on its opening movement swinging downwardly about the axis of its hinge rod and its said hinge rod moving backwardly in said slots along said frame thereby removing said rest from beneath said fore door for opening said fore door.

4. A drop bottom mine car which comprises a pair of side sill members and end sill members providing a frame, a fore door and an aft door in tandem between said side sills, a rotatable fore door hinge rod mounted transverse of said side sills and having the forward end of said fore door secured thereto, said hinge rod providing a pivot mounting about which said fore door may swing downward for opening, a rotatable aft door hinge rod mounted transverse of said side sills with its ends extending through elongate slots in said side sill members which slots are downwardly inclined toward the rear, said aft door hinge rod having the forward end of said aft door secured thereto, a roller mounted on each end of said aft door hinge rod outside said side sill members, a trackway on each side sill member under and outside said side sill members and providing means for rolling movement of said rollers thereon a limited distance back and forth along said frame, said aft door hinge rod, rollers, and trackways providing means whereby said aft door may swing downwardly about its hinge rod axis during opening movement and whereby said aft door hinge rod moves backward on

the frame within said inclined slots during the opening movement and forward on the frame within said inclined slots during the closing movement of said aft door, the forward end of said aft door providing a rest upon which the rear end of said fore door rests when the fore door is in closed position and said aft door hinge rod is in forward position within said inclined slots, wedge means on said frame to engage said aft door and force it and its hinge rod to forward position within said inclined slots during the closing movement of said aft door so that its forward end is under the rear end of the fore door when the fore door is swung up to closed position, latch mechanism operative to hold said aft door in closed position and to release said aft door for opening, said aft door on its opening movement swinging downwardly about the axis of its hinge rod and its said hinge rod moving backwardly and downwardly within said inclined slots along said frame thereby removing said rest from beneath said fore door for opening said fore door.

5. A drop bottom mine car which comprises a pair of side sill members and end sill members providing a frame, a fore door and an aft door in tandem between said side sills, a rotatable fore door hinge rod mounted transverse of said side sills and having the forward end of said fore door secured thereto, said hinge rod providing a pivot mounting about which said fore door may swing downward for opening, a rotatable aft door hinge rod mounted transverse of said side sills and having the forward end of said aft door secured thereto, a roller mounted on each end of said aft door hinge rod, a trackway on each side sill providing means for rolling movement of said rollers thereon a limited distance back and forth along said frame, said aft door hinge rod, rollers, and trackways providing means whereby said aft door may swing downwardly about its hinge rod axis during opening movement and whereby said aft door hinge rod moves backward on the frame during the opening movement and forward on the frame during the closing movement of said aft door, the forward end of said aft door providing a rest upon which the rear end of said fore door rests when the fore door is in closed position and said aft door hinge rod is in forward position, a roller mounted for rotation on the rear end of said aft door, wedge means on said frame to engage said roller on the aft door and force said aft door and its hinge rod to forward position during the closing movement of said aft door so that its forward end is under the rear end of the fore door when the fore door is swung up to closed position, latch mechanism operative to hold said aft door in closed position and to release said aft door for opening, said aft door on its opening movement swinging downwardly about the axis of its hinge rod and its said hinge rod moving backwardly along said frame thereby removing said rest from beneath said fore door for opening said fore door.

6. A drop bottom mine car which comprises a pair of side sill members and end sill members providing a frame, a fore door and an aft door in tandem between said side sills, a rotatable fore door hinge rod mounted transverse of said side sills and having the forward end of said fore door secured thereto, said hinge rod providing a pivot mounting about which said fore door may swing downward for opening, a rotatable aft door hinge rod mounted transverse of said side sills and extending through elongate slots in each

side sill member, said hinge rod having the forward end of said aft door secured thereto, a roller mounted for rotation on each end of said aft door hinge rod, a trackway on each side sill member adjacent said slots providing means for rolling movement of said rollers thereon a limited distance back and forth along said frame, said hinge rod, rollers, and trackways providing means whereby said aft door may swing downwardly about its hinge rod axis during opening movement and whereby said aft door hinge rod moves backward on the frame within said slots during the opening movement and forward on the frame within said slots during the closing movement of said aft door, the forward end of said aft door providing a rest upon which the rear end of said fore door rests when the fore door is in closed position and said aft door hinge rod is in forward position within said slots, a stub shaft mounted on said frame parallel with its end, a cam roller mounted on said stub shaft for rotation, wedge means having a cam face on said frame to engage said cam roller and force said aft door and its hinge rod to forward position during the closing movement of said aft door so that its forward end is under the rear end of the fore door when the fore door is swung up to closed position, latch mechanism operative to hold said aft door in closed position and to release said aft door for opening, said aft door on its opening movement swinging downwardly about the axis of its hinge rod and its said hinge rod moving backwardly within said slots along said frame thereby removing said rest from beneath said fore door for opening said fore door.

7. A drop bottom mine car which comprises a pair of side sill members and end sill members providing a frame, a fore door and an aft door in tandem between said side sills, a rotatable fore door hinge rod mounted transverse of said side sills and having the forward end of said fore door secured thereto, said hinge rod providing a pivot mounting about which said fore door may swing downward for opening, a rotatable aft door hinge

rod mounted transverse of said side sills and extending through elongate slots in each side sill member, said hinge rod having the forward end of said aft door secured thereto, a link on each side sill pivoted at its upper end for swinging movement and having a bore at its lower end, the ends of said aft door hinge rod being mounted for rotation in said bores of said links, a roller mounted for rotation on each end of said aft door hinge rod, a trackway on each side sill member adjacent said slots providing means for rolling movement of said rollers thereon a limited distance back and forth along said frame, said hinge rod, link, rollers, and trackways providing means whereby said aft door may swing downwardly about its hinge rod axis during opening movement and whereby said aft door hinge rod moves backward on the frame within said slots during the opening movement and forward on the frame within said slots during the closing movement of said aft door, the forward end of said aft door providing a rest upon which the rear end of said fore door rests when the fore door is in closed position and said aft door hinge rod is in forward position within said slots, a stub shaft mounted on said frame parallel with its end, a cam roller mounted on said stub shaft for rotation, wedge means having a cam face on said frame to engage said cam roller and force said aft door and its hinge rod to forward position during the closing movement of said aft door so that its forward end is under the rear end of the fore door when the fore door is swung up to closed position, latch mechanism operative to hold said aft door in closed position and to release said aft door for opening, said aft door on its opening movement swinging downwardly about the axis of its hinge rod and its said hinge rod moving backwardly within said slots along said frame thereby removing said rest from beneath said fore door.

THOMAS EARL BOWEN.
